UNITED STATES PATENT OFFICE.

ALBERT C. ARNETT, OF SHILO SPRINGS, OHIO.

DESIGN FOR A LIGHT REFLECTOR.

Application filed June 7, 1921. Serial No. 475,734. Term of patent $3\frac{1}{2}$ years.

To all whom it may concern:

Be it known that I, ALBERT C. ARNETT, a citizen of the United States of America, residing at Shilo Springs, county of Montgomery, State of Ohio, have invented a new, original and ornamental Design for Light Reflector, of which the following is a specification, reference being had to the accompanying drawing, forming a part thereof.

In the drawing, Fig. 1 is a perspective

view and Fig. 2 a diametrical sectional view of the light reflector, showing my new design.

I claim:

The ornamental design for a light reflector, as shown.

In testimony whereof I have hereunto set my hand this 31st day of May, A. D. 1921.

ALBERT C. ARNETT.
